UNITED STATES PATENT OFFICE.

WILLIAM MCALLISTER, OF LAWRENCE, MASSACHUSETTS.

YARN-PRINTING MACHINE.

SPECIFICATION forming part of Letters Patent No. 242,952, dated June 14, 1881.

Application filed December 18, 1880. (Model.)

To all whom it may concern:

Be it known that I, WILLIAM MCALLISTER, of Lawrence, in the county of Essex and State of Massachusetts, have invented certain new and useful Improvements in Machines for Printing Yarn for Carpeting, &c., of which the following is a specification.

The objects of my invention are to provide a machine for printing yarn with hot colors for carpetings, &c., and upon any kind of yarn, either wool, cotton, silk, hemp, or jute, with any desired number of colors, so that when the same is woven in the usual manner the intended design or pattern may appear upon the fabric, as hereinafter fully explained; and it consists in the construction and use of a series of color-guides having a design or pattern represented thereon, and adapted for use with a case having a series of shields, whereby the several colors may be indicated which are to be placed in a corresponding series of color-cells, in order to print the thread or yarn in such manner as to produce the same design when it is woven into the fabric; and it further consists in the combination of a pair of grooved printing-rolls, each having a series of ribs which coincide with the grooves in the opposites, with a cubical yarn-holder and adjustable pressure-rolls, by which the yarn-holder may be held in contact with the printing-rolls; and it further consists in the combination of such printing-rolls with a cubical yarn-holder, whereby a series of colors may be printed across the yarn wound thereon and upon the entire surface of one of the four sides of such yarn-holder at a single operation or movement of the same through the machine; and it further consists in the construction and combination of a collapsible cubical yarn-holder provided with a removable jacket, whereby the printed yarn may be removed upon said jacket from the yarn-holder and placed upon bars to dry, and a separate jacket placed over the yarn-holder preparatory to receiving thereon uncolored or white yarn or unprinted yarn, ready for the printing to be repeated.

Figure 1 represents a perspective view of a yarn-printing machine embracing my invention. Fig. 2 represents a vertical longitudinal section of the machine, excepting the yarn-holder, of which is shown a side view. Fig. 3 represents an elevation of one of the sides of

the yarn-holder made adjustable. Fig. 4 shows a series of color-guides. Fig. 5 shows the color-guide case with guide.

A represents a suitable frame to retain in proper position the several devices, and B represents a heated metal plate or stone or other heat-distributing device, whereby the dyes or colors placed in the series of cells E may be kept at the desired temperature, and are made adjustable vertically by the inclined surfaces C being operated by a suitable screw, D, so as to slide the cell-frame bed F back and forth as desired.

I have shown the color-cells E in two series, E and E'; but the cells or boxes may be constructed of any suitable sheet metal—copper, preferably—and each formed separate and placed upon the heating device B, and are adapted to be adjusted horizontally as desired.

Mounted in the frame A in suitable bearings are the metal printing-rolls G G', having peripheral grooves, which form the printing-ribs 75 H, the ribs in or upon the roll G being formed or constructed so as to exactly coincide with the grooves in the roll G', and the ribs H' upon this roll G' are in exact line with the grooves in roll G, so that the two series of printing-ribs H and H' shall exactly cover the length of the said rolls G G', so as to produce upon the yarn I any variety of colors or shades, each of which shall exactly meet the colors contiguous thereto on each single thread thereof.

Above the horizontal printing-rolls G G' are secured suitably-constructed guideways J J', to which is nicely fitted a sliding carrier-frame, K, within which is mounted, by journals L at each end, the cubical yarn-holder M, one side of which is adjustable or contractible, so as to reduce the external diameter. This may be accomplished in a variety of ways, one of which consists in forming one of the sides or faces of the holder in three pieces—the central one, N, wedge-shaped or tapering, and the two outer pieces, O, being formed upon the same angle on their meeting edges, and pivoted at their wider ends, so that when the piece N is drawn out the side pieces, O, may be forced inwardly, to permit 100 a water-proof or water-repellent jacket, P, to be placed thereon readily, and the wedge-shaped piece N introduced between the said side pieces, O, so as to expand the holder M,

which act would cause the said jacket P to fit snugly thereon preparatory to the introduction thereon of the yarn or thread I by winding the same in a single layer, or one thread deep, and 5 closely together throughout the external surface of the said jacket P. When the threads or yarn have been thus applied, the "holder" being mounted on the carrier-frame K and brought beneath the adjustable rolls V, then 10 carried or forced or drawn through the machine by suitable gear mechanism, S, attached to the journals of the printing-rolls, whereby power and motion may be imparted thereto, so as to actuate the said yarn-holder when 15 brought between the said rolls and the adjustable friction-rolls, as shown, said printing-rolls G G' take upon the ribs thereof from the dye-cells the various colors placed therein, as before described, and impart the said colors in 20 lines across the series of threads upon the under side of the said holder, or upon that surface which contacts with the printing-rolls, and when the same has been sufficiently printed the holder M is adjusted or turned so as to 25 present the next face to the action of the printing-rolls; and in order to save time and labor I contemplate its passage or movement through the said machine in the reverse or opposite direction by any suitable mechanism, as heretofore employed and well understood, and which need not be further described in this connection. When printed upon all sides, or entire, the jacket, with the yarn or thread thereon, may be removed from the holder and placed 30 35 upon the bars to dry, and the operation repeated or continued until the desired quantity of yarn or thread has been printed, containing that portion of the pattern shown upon the color-guide R, No. 1, when the next color-guide, 40 No. 2, is to be employed to arrange the color-cells E by transposition thereof, or such refilling and introduction of new colors as the guide R may require when placed into the color-guide case S', as shown in Fig. 5, where- 45 in it will be understood that the colors seen through the openings t therein, when the said color-guide R is inserted so as to reach the stop or opposite end of the said case S', are to indicate the colors that are to be placed or con- 50 tained in that part or series of color-cells which distribute the colors to the printing-faces of the ribs of printing-roll G, and when the said series of cells have been filled or supplied, as

indicated, the said color-guide R is to be drawn outward one space, or so as to bring the colors 55 previously seen under the bars or shields v, then proceed to fill or arrange the series of color-cells which are to distribute or supply the printing-rolls upon the printing-roll G' in accordance with the colors as seen in this position of the color-guide, and then proceed as before, and until each "color-guide" employed in forming the pattern or design has been proceeded with, as described.

The color-guide may represent the color to 65 be printed upon one or more threads, and may vary in number as the various designs may require, adapted to Brussels, tapestries, or other carpetings or fabrics produced by weaving or knitting.

Having thus described my invention, what I claim is—

1. The color-guides R, having a design or pattern represented thereon, and adapted for use with the case S', having shields v, whereby the several colors are indicated which are to be placed within a corresponding series of color-cells, in order to print the thread or yarn in such manner as to produce the same design when it is woven into fabric, substantially as 75 and for the purposes set forth.

2. The combination of the pair of grooved printing-rolls, each having a series of ribs which coincide with the grooves in the opposites, with a cubical yarn-holder and pressure- 85 rolls, substantially as described, as and for the purposes set forth.

3. The combination, with the pair of printing-rolls, as above described, of the cubical yarn-holder, whereby a series of colors may be 90 printed across the yarn wound thereon and upon the entire surface of one of the four sides of said yarn-holder at a single movement of the same through the machine, substantially as described, as and for the purposes set forth. 95

4. The combination, with the collapsible cubical yarn-holder, of the removable jacket, whereby the yarn wound thereon, when printed entire, may be removed from said holder with the jacket, substantially as and for the purposes set forth. 100

WILLIAM McALLISTER.
